CRATES, PARTICULARLY BOTTLE CRATES

Henrik Mannheimer, Goteborg, Sweden

Application October 8, 1957, Serial No. 688,907

Claims priority, application Sweden October 9, 1956

2 Claims. (Cl. 220—97)

The present invention relates to crates, particularly bottle crates, of the kind in which the under side of the crate bottom is provided with a frame situated below a plane through the lower edges of the crate walls, which frame, when a number of crates are piled atop each other, serves as a guide for the crates.

Especially when transporting crates by means of mechanical conveyors, and more particularly when the crates are heavily loaded, these frames are subject to excessive wear, necessitating frequent and costly repair.

In the crate according to the present invention, the risk for wear has been highly reduced. The crate is essentially characterized in that the bottom is freely movable in a vertical direction between two stop positions, in the upper of which the under surface of the frame is situated in or above said plane through the lower edges of the crate walls.

A preferred embodiment of the invention is characterized by the fact, that in the lower stop position the bottom rests against a flange parallel to the bottom and formed by a metal strip of angular cross-section placed around the crate and forming the lower part of the crate walls.

One embodiment of the invention is illustrated in the accompanying drawing in which:

Figure 1 is a side elevation of a crate according to the invention;

Figure 2 is a top plan elevation of the crate with one corner portion of the walls cut away;

Figure 3 shows the crate from the under side; and

Figure 4 is a vertical cross-section through a couple of crates placed one atop the other.

The four walls 1 of the right-angled crate may for instance be made from plywood, and to the lower portion of said walls there is attached, by means of screws 2, the vertical flange 4 of a strip in the form of an angle iron surrounding the crate. The crate bottom 6, the under side of which is provided with a frame 6a, is freely movable vertically between the second, horizontal flange 5 of the angle iron and the lower edge of the main body of the walls 1.

As will be evident from the upper portion of Figure 4, the bottom 6 of a crate placed atop another crate will

2

be situated in a lower stop position, resting against the horizontal flanges 5 of the angle iron with the frame 6a situated below a plane through the flanges 5 which constitute the lower edges of the crate walls. The frame 6a thereby serves as a guide between the crates. When the crate is placed upon a plane surface (as is shown in the lower portion of Figure 4), the bottom 6 will be raised from the aforesaid position to a position in which the under side of the frame 6a is situated in the plane of the flanges 5. In this way, the angle iron of the lowermost crate in a pile will take up the weight of the other crates in the pile. The frame 6a of the lowermost crate in the pile will thus not be subject to any appreciable wear, inasmuch as it supports only the contents of the lowermost crate.

The invention is not limited to the embodiment hereinbefore described and as shown in the accompanying drawing, other embodiments being conceivable within the scope of the invention.

20 What I claim is:

1. A stacking crate comprising a crate body having an open top and bottom, a bottom member capable of and loosely positioned for extending across said crate body open bottom, means extending from said crate body at 25 the open bottom thereof forming a base for supporting said crate when positioned on a surface and having said bottom member positioned therein, said means including an inwardly extending lateral flange with said bottom member loosely positioned between and limited 30 in its movement by said flange and said crate body and said body member having an extension capable of extending outwardly of said flange when said bottom member rests on said flange for serving as a guide in the stacking of said crate on an open top crate therebeneath.
- 35 2. A stacking crate comprising a crate body having an open top and bottom, an angle member having one side connected to the exterior of and extending from said crate body bottom portion with another side of said angle member extending inwardly and laterally of said 40 crate body forming a base for said crate, a bottom member slidably positioned between and extending laterally of the first mentioned side of said angle member, said angle member second side and said crate body forming stops limiting the sliding of said bottom member to and 45 from said crate body at the open bottom thereof and a frame connected to said bottom member and extending therefrom which frame is capable of extending outwardly of said angle member second side when said bottom member is positioned on said second side forming a guide for stacking said crate on a crate therebelow and being positioned within said angle member when said bottom member contacts said crate body.
